SHOE FORM

Filed April 25, 1929

UNITED STATES PATENT OFFICE

WILLIAM J. DE WITT, OF AUBURN, NEW YORK, ASSIGNOR TO SHOE FORM CO., INC., OF AUBURN, NEW YORK, A CORPORATION OF NEW YORK

SHOE FORM

Application filed April 25, 1929. Serial No. 357,948.

This invention relates to improvement in show forms more particularly those which comprise a hollow toe member of resilient materials such as celluloid and a cross bar suitably attached to the walls of the toe member so that by the movement of the cross bar the width of the toe member may be increased or decreased.

This invention is shown and described as applied to a toe member having ball flanges, one end of the cross bar being pivotally mounted on one of the flanges and the other flange being provided with guiding means which coact with the cross bar so that the pivotal movement of the cross bar causes an increase or decrease in the width of the toe member. In adjusting the toe member to the proper width it is desirable that the pivotal movement of the cross bar be a slow or gradual one so that it can be quickly checked when the desired width is attained.

One object of this invention is to provide frictional acting means which will continuously resist this pivotal movement of the cross bar and more particularly to provide frictional means of the same material as that of which the toe member is made. Another object of this invention resides in the provision of an element preferably, though not necessarily in the form of a disc, movable by the cross bar over the flange of the toe member and in contact therewith and which may be of the same material as that of which the toe member is made. A further object of the invention is to provide a friction element which, when the cross bar has been swung to that position which gives the toe member the proper width, may be rigidly secured to the flange thus preventing any movement of the cross bar out of the desired position.

Other objects of the invention will appear from a consideration of the following specification taken in connection with the drawings which form a part thereof and in which Figs. 1 and 2 are bottom plan views of shoe forms embodying this invention and differing from each other in the means of associating the cross bar with one of the flanges of the toe member;

Fig. 3 is a similar view of a shoe form

embodying this invention, the cross bar being rigidly fixed in the position in which the toe member is of the proper width;

Fig. 4 is a sectional view taken along the line 4—4 of Fig. 3 illustrating more clearly the method of securing the disc in place; 55

Fig. 5 is a bottom plan view of another improvement of this invention in which the retarding element forms an integral part of the slotted flange of the toe member; 60

Fig. 6 is a sectional view along the line 6—6 of Fig. 5; and

Fig. 7 is another sectional view along the line 7—7 of Fig. 5. 65

The toe member of the shoe form illustrated in Figs. 1 to 4 inclusive is designated by the numeral 10 and includes opposite side walls 11, 12 which terminate in ball flanges 13 and 14 respectively. The walls 11 and 12 of the toe member are joined by a cross bar 15 pivotally connected at one end to the flange 13 by a rivet 16 or other suitable means. In the flange 14 is formed an arcuate slot 17 which receives a button 18 or other form of movable member attached to the other end of the cross bar 15. Mounted upon the button 18 between the end of the cross bar 15 and the flange 14 is placed a disc 20 preferably of the same resilient material as that of which the toe member is formed. The disc 20 is in frictional contact with the upper surface of the flange 14 so that the frictional engagement resists the pivotal movement of the cross bar 15. 70 75 80

When the cross bar 15 has been moved into that position at which the toe member 10 is of the proper width it may be fixed in that position by attaching the disc 20 to the surface of the flange 14. If the disc 20 be, as is particularly desirable, of the same material as the toe member, preferably celluloid, this securing of the disc to the flange may be done by inserting acetone between the surfaces. Fig. 4 illustrates somewhat exaggeratedly a layer 21 of adhesive between the disc 20 and the flange 14. It will be understood, however, that the adhesive here indicated is very much enlarged in order to bring out this feature and that, as a matter of fact the two surfaces would be integrally joined if acetone be supplied to the surfaces in contact. 85 90 95 100

The embodiment shown in Figs. 5, 6 and 7 differs from that previously described merely in the manner of resisting the pivotal movement of the cross bar. The same reference characters therefor will be used to designate the parts in common and no particular description of such parts or of their coaction is believed to be necessary. In place, however, of the disc 20 shown in the first embodiment there is provided an elongated boss 30 which is struck up from the surface of the flange 14 as is most clearly shown in Figs. 6 and 7. The crown of the boss 30 bears against the cross bar 15 and thus offers resistance to the free pivotal movement of the cross bar. The boss 30 is preferably arcuate and can be struck up at the same time that the slot 17 is formed in the flange 14.

In both of the embodiments described it will be noted that the free pivotal movement of the cross bar 15 is resisted by frictionally acting means preferably of the same material as the toe member. The first embodiment, however, discloses in addition to this feature that of permanently securing the cross bar at any desired stage of its pivotal movement. A shoe form of the type shown in Figs. 1 to 4 inclusive may be made up in quantities and supplied to manufacturers and other users. These shoe forms are then set to the widths of the shoes with which they are to be used and when the proper width has been attained the cross bar is held against pivoting from that position by the application of a suitable adhesive between the upper surface of the flange 14 and the disc 20. As pointed out above the toe members are usually made of such resilient material as celluloid and when so made the application of acetone will cause a fusion of the celluloid of the disc with the celluloid of the flange. If the disc 20 be made of material other than celluloid, it will, however, be rigidly secured to the flange by the use of the proper adhesive. The use of adhesive to secure these parts in position is only one way of so doing and instead thereof the disc 20 may be attached to the flange by rivets or other forms of fastening means which are well known to those skilled in the art and which therefore are not illustrated.

The showing and description in this application of two embodiments only of this invention obviously does not limit me thereto since other embodiments of this invention can be made without departing from the spirit and scope of the invention as set forth in the following claims.

I claim:

1. A shoe form comprising a hollow toe member of resilient material having ball flanges on the side walls thereof, a cross bar pivoted at one end upon one of said flanges, guiding means on the other of said flanges coacting with said cross bar whereby a sliding

engagement is provided between said cross bar and said second named flanges, the pivotal movement of said cross bar causing the toe member to increase or decrease in width, and means frictionally and continuously resisting such pivotal movement. 70

2. A shoe form comprising a hollow toe member of resilient material having ball flanges on the side walls thereof, a cross bar pivoted at one end upon one of said flanges, 75 guiding means on the other of said flanges coacting with said cross bar whereby a sliding engagement is provided between said cross bar and said second named flanges, the pivotal movement of said cross bar causing 80 the toe member to increase or decrease in width, and means movable over the second named flange in surface contact therewith by said cross bar for frictionally resisting such pivotal movement. 85

3. A shoe form comprising a hollow toe member of resilient material having ball flanges on the side walls thereof, a cross bar pivoted at one end upon one of said flanges, 90 guiding means on the other of said flanges coacting with said cross bar whereby a sliding engagement is provided between said cross bar and said second named flanges, the pivotal movement of said cross bar causing the toe member to increase or decrease in width, 95 and means movable over the second named flange by said cross-bar, said means being in surface contact therewith and of the same material as that of which the toe member is made for frictionally resisting such pivotal movement. 100

4. A shoe form comprising a hollow toe member of resilient material having ball flanges on the side walls thereof, a cross bar pivoted at one end upon one of said flanges, 105 the other of said flanges being provided with a guiding slot, an element movable in said slot and attached to the other end of the cross bar whereby a sliding engagement is provided between the cross bar and the slotted flange, the pivotal movement of the cross bar causing the toe member to increase or decrease in width, and means on the slotted flange adjacent the slot therein in surface contact with the cross bar for frictionally 110 and continuously resisting such pivotal movement. 115

5. A shoe form comprising a hollow toe member of resilient material having ball flanges on the side walls thereof, a cross bar 120 pivoted at one end upon one of said flanges, the other of said flanges being provided with a guiding slot, an element movable in said slot and attached to the other end of the cross bar whereby a sliding engagement is provided 125 between the cross bar and the slotted flange, the pivotal movement of the cross bar causing the toe member to increase or decrease in width, and means moved by the cross bar in surface engagement with the 130

slotted flange adjacent the slot and of the same material as that or which the toe member is made for frictionally resisting such movement.

- 5 6. A shoe form comprising a hollow toe member of resilient material having ball flanges on the side walls thereof, a cross bar pivoted at one end upon one of said flanges, the other of said flanges being provided with 10 a guiding slot, an element movable in said slot and attached to the other end of the cross bar whereby a sliding engagement is provided between the cross bar and the slotted flange, the pivotal movement of the cross bar causing the toe member to increase or decrease in width, and means on the movable element and bearing against the slotted flange for frictionally resisting such pivotal movement.
- 15 7. A shoe form comprising a hollow toe member of resilient material having ball flanges on the side walls thereof, a cross bar pivoted at one end upon one of said flanges, the other of said flanges being provided with 20 a guiding slot, an element movable in said slot and attached to the other end of the cross bar whereby a sliding engagement is provided between the cross bar and the slotted flange, the pivotal movement of the cross bar causing the toe member to increase or decrease in width, and means on the movable element of the same material as the toe member and bearing against the slotted flange for frictionally resisting such pivotal movement.
- 25 8. A shoe form comprising a hollow toe member of resilient material having ball flanges on the side walls thereof, a cross bar pivoted at one end upon one of said flanges, the other of said flanges being provided with 30 a guiding slot, an element movable in said slot and attached to the other end of the cross bar whereby a sliding engagement is provided between the cross bar and the slotted flange, the pivotal movement of the cross bar causing the toe member to increase or decrease in width, and means on the movable element of the same material as the toe member and bearing against the slotted flange for frictionally resisting such pivotal movement.
- 35 9. A shoe form comprising a hollow toe member of resilient material having ball flanges on the side walls thereof, a cross bar pivoted at one end upon one of said flanges, the other of said flanges being provided with 40 a guiding slot, an element movable in said slot and attached to the other end of the cross bar whereby a sliding engagement is provided between the cross bar and the slotted flange, the pivotal movement of the cross bar causing the toe member to increase or decrease in width, and a disc of the same material as the toe member, clamped by the movable element against a surface of the slotted flange for frictionally resisting such pivotal movement.
- 45 10. A shoe form comprising a hollow toe member of resilient material having ball flanges on the side walls thereof, a cross bar pivoted at one end upon one of said flanges, the other of said flanges being provided with 50 a guiding slot, an element movable in said slot and attached to the other end of the cross bar whereby a sliding engagement is provided between the cross bar and the slotted flange, the pivotal movement of the cross bar causing the toe member to increase or decrease in width, and a disc clamped by the movable element against a surface of the slotted flange and permanently secured to the flange when

the desired width of the toe member has been attained by the pivotal movement of the flange.

10. A shoe form comprising a hollow toe member of resilient material having ball flanges on the side walls thereof, a cross bar pivoted at one end upon one of said flanges, the other of said flanges being provided with a guiding slot, an element movable in said slot and attached to the other end of the cross bar whereby a sliding engagement is provided between the cross bar and the slotted flange, the pivotal movement of the cross bar causing the toe member to increase or decrease in width, and a disc of the same material as the toe member clamped by the movable element against a surface of the slotted flange and adhesively secured thereto when the desired width of the toe member has been attained by the pivotal movement of the flange.

11. A shoe form comprising a hollow toe member of resilient material having ball flanges on the side walls thereof, a cross bar pivoted at one end upon one of said flanges, the other of said flanges being provided with a guiding slot, an element movable in said slot and attached to the other end of the cross bar whereby a sliding engagement is provided between the cross bar and the slotted flange, the pivotal movement of the cross bar causing the toe member to increase or decrease in width, and a disc of the same material as the toe member carried by the movable element and adhesively secured to the slotted flange when the desired width of the toe member has been attained by the pivotal movement of the flange.

12. A shoe form comprising a hollow toe member of resilient material having ball flanges on the side walls thereof, a cross bar pivoted at one end upon one of said flanges, the other of said flanges being provided with a guiding slot, an element movable in said slot and attached to the other end of the cross bar whereby a sliding engagement is provided between the cross bar and the slotted flange, the pivotal movement of the cross bar causing the toe member to increase or decrease in width, and a disc carried by the movable member and held thereby in frictional contact with the surface of the slotted flange to resist the pivotal movement of the cross bar.

13. A shoe form comprising a hollow toe member of resilient material having ball flanges on the side walls thereof, a cross bar pivoted at one end upon one of said flanges, the other of said flanges being provided with a guiding slot, an element movable in said slot and attached to the other end of the cross bar whereby a sliding engagement is provided between the cross bar and the slotted flange, the pivotal movement of the cross bar causing the toe member to increase or decrease in width, and a disc clamped by the movable element against a surface of the slotted flange and permanently secured to the flange when

crease in width, and a disc of the same material as the toe member carried by the movable member and held thereby in frictional contact with the surface of the slotted flange to resist the pivotal movement of the cross bar.

Signed by me at Auburn, N. Y., this 18th day of April, 1929.

WILLIAM J. DE WITT.
